CONTROL APPARATUS

Allen T. Joze, Chicago, Ill., assignor to James E. Johnson, Chicago, Ill.

Application November 19, 1937, Serial No. 175,362

9 Claims. (Cl. 194—9)

This invention relates to amusement devices and has more particular reference to control apparatus of the token or coin controlled type for controlling amusement or vending machines, games, and the like.

An object of the invention is the provision of a novel and an improved control apparatus of the coin controlled type.

Another object of the invention is the provision of a multi-coin controlled apparatus adapted to receive one or more tokens or coins of a particular denomination and adapted to selectively control a plurality of amusement, game, or vending units determined by the number of received tokens or coins.

It will be understood that some games and vending, as well as amusement, machines include a plurality of playing, amusement dispensing, and article dispensing units which are selectively operable in the case of such a vending machine, for example, to dispense, for instance, different brands of candy, chewing gum, or other articles. The novel control apparatus is adapted to control such units and, of course, may have other uses.

A further object of the invention is the provision of such control apparatus which may be readily adapted for control by tokens or coins of different denominations.

Another object of the invention is the provision in such a token or coin controlled apparatus of novel fraud resisting means for discouraging or resisting attempts to employ spurious coins or tokens or coins not intended to be accepted by the novel control apparatus.

A further object of the invention is the provision of such control apparatus wherein one or more tokens or coins, or some tokens and some coins, are receivable therein to govern the selective control action and wherein the accepted coins are automatically separated from the accepted tokens.

Another object of the invention is to provide a plurality of token or coin chutes in such control apparatus with means for rendering a plurality of the last tokens or coins inserted in each chute visible from outside of the apparatus.

A further object of the invention is to provide a plurality of token or coin receiving chutes in such novel control apparatus adapted to receive tokens or coins of substantially the same size or denomination and to associate token or coin operable means with each such chute respectively operable by each token or coin received in the chutes.

Other objects of the invention, including the novel arrangements and combinations of elements, will become apparent from the following description of a preferred embodiment of the invention as illustrated in the accompanying drawings wherein the same reference characters are employed to designate similar parts throughout the several views and in which:

Fig. 1 is an end elevation of a portion of a control apparatus of the coin controlled type embodying the features of the invention, the illustrated control apparatus being shown in its initial or normal position;

Fig. 2 is a fragmentary end elevation partially in cross section of the control apparatus showing the means for preventing its operation without at least one token or coin;

Fig. 3 is a partial plan view of the novel coin-handling apparatus shown in Fig. 1;

Fig. 4 is an end elevation similar to that shown in Fig. 1, but showing the relation of certain parts in an operated position;

Fig. 5 is a fragmentary end elevation of the control apparatus showing the means for preventing operation of the control apparatus during the operating cycle of a machine controlled by the control apparatus;

Fig. 6 is a partial cross section taken substantially along the lines 6—6 of Fig. 3 and shows the position of the various parts upon the insertion of a token or coin, but before operation of the control apparatus;

Fig. 7 is a partial plan section taken substantially along the lines 7—7 of Fig. 6;

Fig. 8 is a fragmentary cross section taken substantially along the lines 8—8 of Fig. 6;

Fig. 9 is a transverse cross section of a portion of the control apparatus taken substantially along the lines 9—9 of Fig. 1;

Fig. 10 is a cross section similar to that shown in Fig. 6, but showing the relationship of the parts during the operation of the novel control apparatus;

Fig. 11 is a cross sectional detail taken substantially along the lines 11—11 of Fig. 10;

Fig. 12 is a cross sectional detail taken substantially along the lines 12—12 of Fig. 10;

Fig. 13 is a fragmentary perspective view of one form of fraud resisting means employed in the novel control apparatus; and

Fig. 14 is a perspective view of one member for holding a plurality of the last tokens or coins in view within one of the token or coin chutes.

To aid in clearly understanding the invention, it might be well, before proceeding with a de-

tailed description of an embodiment thereof, to describe briefly the operation of the illustrated control apparatus. One or more tokens or coins, or some of each, are inserted in a desired one or plurality of coin receivers, one token or coin being inserted in each of the desired receivers. The coin receivers are movable by manually operable means common to all of them when a token or coin is in any one or more of them, into respective registration with open ends of a plurality of tokens or coin chutes, the forward ends of which are covered with a transparent sheet material for rendering coins or tokens therein visible from outside of the control apparatus.

In that position of the coin receiver, the token or coin in each receiver is released and is deposited in the corresponding coin chute where it co-acts with switch operating means for selectively operating a plurality of electrical switches corresponding in number to the number of coin chutes, and thereafter the token or coin in each chute is positively moved or driven along the chute a distance substantially equal to the diameter of the coin. Such driving of the last token or coin inserted in any chute may be utilized to progress a series of tokens or coins preceding the last deposited token or coin along the chute and out of its outlet end.

It will be understood that the selectively operable switches just referred to above may be respectively connected in electrical operating circuits of, for example, the vending units of a vending machine, so that the operation of the switches or any of them will cause the operation of the corresponding vending unit or units. After such unit or units have been thus selected and operated, another token or coin, or a plurality of either or both of them, may be employed to permit subsequent operation of the control apparatus. To facilitate counting the revenue collected, the apparatus is provided with means at the outlet ends of the coin chutes for separating the tokens from the coins in each chute. In order to resist or discourage fraudulent attempts to operate the control apparatus, it is provided with means which not only requires at least one token or coin to control the operation, but it also requires that the token or coin employed be of a predetermined size or denomination and thickness, and where magnetic slugs are employed in an attempt to defraud the apparatus, even though they be of the proper size and thickness, they will be separated from acceptable tokens and coins and returned to an accessible position outside of the apparatus without operating the electrical switches for controlling the vending units just referred to above.

Illustrative of the invention, a suitable frame is employed for carrying the various means included in the novel control apparatus in operative relationship. Such a frame comprises a pair of frame members 11 and 12 having upstanding portions 13 and 14 and forwardly extending lower portions 15 and 16 with downwardly and forwardly inclined upper ends. Each of those frame members is provided in its upper end with an elongated slot 17; laterally rearwardly of the forwardly extending portion 15, 16, with an aperture 18 having at its upper forward end a slot 19 communicating therewith; and intermediate the slot 17 and the aperture 18 with an arcuate aperture 21.

Those frame members 11 and 12 are held in spaced relationship by connecting members 22, 23, 24, and 25. The connecting member 22 spans

between the upright frame members, is removably secured as at 26 on the upper forward ends of the portions 13 and 14, and is provided with a series of apertures 27 spaced longitudinally of the connecting member and each adapted to receive one token or coin at a time therein.

The connecting member 23 is secured at its opposite ends to the forward sides of the frame portions 13 and 14 near the upper ends thereof. 10 The connecting member 24 is suitably secured at its opposite ends to the forward ends of the lower frame portions 15 and 16. And the connecting member 25 is secured on supporting member 28 (Fig. 6) arranged at suitable inclinations on the 15 inner faces of the forwardly extending lower frame portions 15 and 16 to support the member 25 at an inclination corresponding generally to that of the upper ends of the portions 15 and 16.

That connecting member 25 serves as a portion 20 of a plurality of token or coin chutes 29 corresponding in number and spacing to the number and spacing of the coin receiving apertures 27. For that purpose the member 25 is adapted to extend from adjacent the upper side of the connecting member 24 rearwardly at an upward inclination beyond the frame member 23 and to curve upwardly as at 31 at its inner or rear side. In spaced relation between the frame members 11 and 12 a plurality of partitions 32 are provided 30 on the upper surface of the curved frame member 25 and extend transversely thereof.

Along the upper face of each such partition 32 an elongated metal strip 33 of greater width than the partition, and having along its side margins 35 a plurality of downwardly extending resilient tabs or members 34, is secured in such a manner that the tabs 34 extend into the coin chutes 29 at opposite sides of the supporting partition for frictionally engaging the coins or tokens as they 40 pass along the chutes. The chutes 29 are covered by a sheet 35 of glass or other transparent material which is suitably secured to the partitions 32 by the same means employed for securing the strips 33 thereon and exemplified at 36 in Figs. 45 3 and 10. It will be seen by reference to Figs. 6 and 10, that the coin chutes 29 are provided with upright open upper ends 37 rearwardly of the frame member 23 and incline downwardly and forwardly therefrom in side-by-side relationship 50 to positions between the frame portions 15 and 16. Thus tokens or coins in any and all of the coin chutes are visible through the glazed sheet 35 from outside the coin control apparatus.

At its curving portion 31 the connecting member 55 25 is provided with a plurality of elongated apertures 38, each communicating with and extending longitudinally of one of the coin chutes 29 to adapt the connecting member for cooperation with means for positively moving or driving 60 coins and tokens forwardly in the coin chutes toward means for separating the coins from the tokens at the forward ends of the chutes. The means for moving or driving the coins and tokens forwardly in the chutes, as illustrated in Figs. 6 65 and 10, comprises a plate 39 reciprocably supported in suitable guides 40 under the coin chutes 29 and having a plurality of elongated apertures 41 therein and a plurality of upstanding lugs or fingers 42 struck up from the plate respectively 70 adjacent the apertures 41, as shown in Fig. 12.

Those lugs 42 are spaced along the plate in alignment with the respective apertures 38, and each lug 42 is movable through the aligned aperture 38 into and out of the corresponding coin chute each time the plate 39 is reciprocated.

The plate 39 has mounted in spaced relation at its rear or inner end a pair of rollers 43. Those rollers are adapted to cooperate with a pair of cam arms 44, each having cam surfaces 45 and 46 at its opposite ends which cooperate with suitable springs 47 to reciprocate the plate 39. The cam arms 44 are fixed intermediate their ends in spaced relation on a shaft 48 journaled intermediate its ends in the frame members 11 and 12 rearwardly of the open upper ends 37 of the coin chutes. The shaft 48 is a part of the operating means of the novel control apparatus, as will presently be described and is rotatable thereby in one direction to cause the cam surfaces 45 to engage the rollers 43 for moving the lugs 42 into the respective coin chutes through the apertures 38. The springs 47 are adapted to return the plate 39 to its initial position with the lugs rearwardly and outside of the coin chutes and in so returning the plate 39 to 20 drive the shaft 48 in the opposite direction toward its initial position. The cam surfaces 45 are so shaped that the forward movement of the lugs 42 resulting from the operation of the cam arms is sufficient to cause each lug to engage a 25 token or coin at the curving portion 31 of the corresponding coin chute and to move the engaged token or coin, together with successively engaged tokens and/or coins forwardly thereof in the same coin chute, toward the forward end 30 of the coin chute a distance substantially equal to the diameter of the coin.

It will be understood that the resilient tabs 34 cooperate with the bottoms of the coin chutes to slidably support a series of adjacent tokens and/or coins in each chute; thus when a coin is moved in any coin chute, as just described, it will move the series of tokens or coins forwardly in that chute a distance substantially equal to the diameter of the coin. Tokens corresponding 40 to the denomination of the coin for which the novel control apparatus is designed, are usually of slightly smaller diameter than the coins. To facilitate counting the returns collected by the novel control device it is desirable to separate 45 such tokens from the coins.

To that end, the forward end of the connecting member 25 is provided with an arcuate slot 49 at the forward end of each of the coin chutes 29, which extends rearwardly of the connecting member 24. On the connecting member 25 a removable strip 51 is mounted by the securing means 36 at one side of each slot 49. Each strip 51 has an edge 52 spaced from the opposite edge of each slot 49, and a beveled margin 53 extending into the next succeeding coin chute. The beveled margin 53 of each strip 51 cooperates with the edge 52 of the next succeeding strip and the margin of the connecting member 25 at the corresponding side of the slot 49 to provide 60 coin supporting guides which are spaced apart to slidably support coins of the proper denomination, but at a distance greater than the diameter of the tokens to be separated. Thus coins are movable along the coin chutes and the coin 65 supporting guides forwardly beyond the connecting member 24, whence they may gravitate into a suitable receptacle not shown. The smaller tokens drop downwardly between the beveled margins 53 and the respectively opposite sides of the slots 49 and through those slots of the coin chutes rearwardly of the connecting member 24 and into a suitable receptacle not shown.

The cam surfaces 46 of the cam arms 44 are adapted to cooperate with token or coin operable 75

switch means which, as already mentioned, may be employed to selectively control, for example, a plurality of vending or amusement units in a vending or amusement machine. Such switch 5 means, as illustrated in Figs. 3, 6, and 10, comprises a group of electrical conductor strips 54 of resilient material for each coin chute 29, and is mounted on a rockable plate 55. The rockable plate 55 is so pivoted at its opposite ends to the inner faces of the frame members 11 and 12 by pivot screws or pins 56 that the forward ends of the groups of strips 54 extend under the respective chutes 29. At one end the strips 54 of each group are insulated, as at 57, from one another and are suitably secured to the plate. At their forward ends the strips of each group carry electrical contact pairs 58. It will be understood that the groups of electrical contacts are connectible by suitable conductors 59 in the operating circuits of the vending or amusement units or other units to be selectively controlled by the control apparatus of the invention.

For operating the switch means the rockable plate 55 carries a pair of rollers 61 forwardly of the pivot pins 56. Those rollers cooperate with the cam surfaces 46 of the cam arms 44 to effect swinging movement of the plate clockwise, as viewed in Fig. 10 while springs 62 swing the plate in opposite direction (when released by latching means later described) whereby the plate 55 is oscillated about its pivot to move the groups of contact-carrying strips 54 to and from positions at which they are operable by coins in the curving portions 31 of the respectively corresponding chutes 29. The coin operable means for operating the switch means comprises a plurality of switch operating pins or members 63. Each such pin 63 is slidably arranged at one end in a hole in the plate 55 and at its opposite end in an apertured bushing 64. One such bushing 64 is secured in the connecting member 25 at one side of the path of each lug 42 and depends from the member 25 into the corresponding elongated aperture 41 of the plate 39, as shown in Fig. 12.

The pins 63 are provided at their lower ends, between the plate 55 and the respective groups of resilient contact-carrying strips 54, with head portions 65 for operating the contacts 58 when the pins are moved in one direction and for cooperating with the plate 55 to limit the movement of the pins in the opposite direction. Normally, with no coin in the curving portion 31 of any coin chute 29, the pins 63 extend into the respective coin chutes. While the cam arms 44 are rotating to cause the cam surfaces 45 and the rollers 43 to move the lugs 42 forwardly in the respective coin chutes 29, the cam surfaces 46 are adapted to swing the plate 55 downwardly to withdraw the pins from the coin chutes. A coin in the curved portion 31 of any coin chute, or each coin in some or all of the curved portions 31 of the coin chutes, is engaged and moved forwardly by the corresponding lug or lugs 42 while the pins 63 are thus withdrawn from the coin chutes.

After the return movement of the cam arms 44 to the position shown in Fig. 6, the next token or coin can gravitate from the respective open upper ends 37 of the coin chutes into the curved portion or portions 31. Thus, when the springs 62 swing the plate 55 upwardly, the token or coin in each curving portion 31 of the coin chute will engage the upper end or ends of the respectively corresponding pins 63 and will stop the movement of the engaged pins to cause the head

portions 65 at their lower ends to close the corresponding contacts 58, as shown in Fig. 6. The other pin or pins 63 entering curving portions 31 without tokens or coins will not be so engaged and will not cause a closing of their corresponding contacts 58.

For receiving a token or coin from any aperture 27, or one from each of some or all of the apertures 27, and transferring it to and depositing it in the upper end 37 of the corresponding coin chute 29, novel means, preferably in the form of a pair of substantially inverted U-shaped assemblies 66 and 67, are pivotally arranged between the upright frame members 11 and 12. The assembly 66 comprises a pair of bars 71 and 72 spaced apart by a plurality of strips 73 therebetween, spaced from one another longitudinally of the bars sufficiently to provide a plurality of passages 74 corresponding in number and spacing to the apertures 27 and open at their opposite ends. Those bars 71 and 72 are suitably secured at their opposite ends to the upper ends of a pair of supporting arms 75 which are respectively pivoted at their lower ends on the inner ends of pivot bolts or pins 76 anchored intermediate their ends in the frame members 11 and 12.

The assembly 66 is swingable, between a receiving position (Fig. 6) at which the passages 74 are respectively in alignment under the apertures 27 and a depositing position (Fig. 10) at which the passages 74 are respectively in alignment over the open upper ends 37 of the coin chutes 29, by the assembly 67 and springs 77. Each spring 77 extends between the outer end of a pin 78 extending outwardly through the aperture 18 in the upright frame member from a rearwardly extending lug or projection 79 intermediate the ends of each arm 75 and an outwardly extending pin or projection 81 on each forwardly extending frame portion 15, 16. The assembly 67 comprises a strap 82 provided with a plurality of apertures 83 elongated and spaced longitudinally of the strap, a strip 84 adjustably secured by screws 85, passing through the elongated apertures 83, to the rear face of the strap 82, and a pair of arms 86 pivoted at their lower ends on the bolts 76 between the arms 75 and the respective frame members 11 and 12 and suitably secured at their upper ends to rearwardly extending end portions 87 at the opposite ends of the strap 82 for supporting the strap 82 and the strip 84 forwardly adjacent the forward bar 71 of the assembly 66.

For retaining tokens or coins in the open ended passages 74 during the movement of the assembly 66 from its receiving position to its depositing position, the strip 84 is provided with a plurality of spaced coin retaining fingers or projections 88, each of which extends downwardly and rearwardly through an aperture 89 in the forward bar 71 and into one of the passages 74. As shown in Fig. 8, the apertures 89 are larger than the fingers 88 to permit adjustment thereof in the apertures longitudinally of the bars 71. Thus by replacing the removable connecting member 22 with coin receiving slots 27 of appropriate size, adjusting the fingers 88 in the apertures 89 to retain coins of that size in the passages 74, and replacing the removable strips 51 with those of a width to accommodate such coins, the novel control apparatus is adapted to handle tokens or coins of a different denomination or size. Intermediate the ends of each arm 86 a pin 91 is secured and extends outwardly therefrom through the aperture 18 in each frame member 11 and

12. At its outer end each pin 91 has secured thereto one end of a spring 92, the other end of which is secured to the pin 81 for yieldably holding the assembly 67 in its forward position with the pins 91 against the forward ends of the slots 19. The pins 91 outwardly of the frame members 11 and 12 pass through arcuate slots 93 in arcuate links 94 for slidably and pivotally connecting the assembly 67 with the operating means therefor.

Such operating means, as shown in Figs. 1 to 3, comprises a suitable handle 95 fixed on an end of the shaft 48 outwardly of the frame member 12 for manual operation of the shaft whereby to move the assemblies 66 and 67 to the coin depositing position relative to the open ends 37 of the coin chutes, full stroke means controlling the angle of rotation of the shaft 48, and means for returning the shaft and handle after each full operating stroke of the handle.

As illustrated, the full stroke means includes a ratchet disc 96 fixed outwardly of the frame members 11 and 12 on each end of the shaft 48 to rotate therewith. Each ratchet disc 96 is provided with a plurality of ratchet teeth 97 extending about a portion of its periphery between a slot 98 and an enlarged slot 99, and with an arcuate portion 101 extending between the sides of the slots 98 and 99 respectively opposite those defining the toothed portion, thus forming a shoulder 102 at the end of the slot 99 adjacent the arcuate portion 101. The ratchet discs are pivotally connected as at 103 with the respective arcuate links 94 and each disc 96 is associated with a rockable spring-held pawl 104 pivoted on each frame member 11 and 12.

Those pawls 104 are engageable with the ratchet teeth 97 when the ratchet discs are rotated in either direction to prevent reversal of the direction of rotation until the slots 98 or the slots 99 are brought into registration with the pawls. In other words, with the pawls in the slots 98, as shown in Fig. 1, the shaft 48 is rotatable by the handle 95 in a clockwise direction against the action of the springs 47 to rotate the ratchet discs 96 in a clockwise direction against the action of the springs 92 through the angle separating those slots and the slots 99. During such rotation the pawls slidably engage the ratchet teeth 97 and cooperate therewith to prevent rotation of the discs 96 in the opposite direction. When the slots 99, during such rotation, are brought into registration with the pawls 104, the springs of those pawls urge them into the slots 99 and are yieldable to permit slidable engagement between the pawls and ratchet teeth during the return movement of the ratchet discs 96.

Such return movement is effected by the springs 47 acting through the plate 39, the cam arms 44, and the shaft 48. During such return movement, the pawls also cooperate with the ratchet teeth to prevent reversal of their rotation until the slots 98 are again brought into registration with the pawls, whereupon the springs of the pawls urge them into the slots 98 to reset the pawls for subsequent operations of the ratchet discs by the handle 95. The arcuate apertures 93 in the links 94 permit idling movement of the links relative to the pins 91 while the springs 47 are returning the plate 39 rearwardly to remove the lugs 42 from the coin chutes 29 and to drive the shaft 48, and hence the ratchet discs 96 and the handle 95, toward their initial positions, as just described.

Fixed on the shaft 48 to rotate therewith between each frame member 11 and 12 and each ratchet disc 96 is an arm or cam 48a which is rockable to and from engagement with a stop or limit pin 48b extending outwardly from each frame member 11 and 12. The arms 48a in their normal positions against the stop pins 48b extend forwardly and engage under the rear ends of locking levers 67a which are respectively pivoted by screws or pins 67b on the frame members 11 and 12 forwardly of the stop pins 48b. Each of those locking levers 67a is provided intermediate its ends with a shoulder 67c for cooperating with the pins 91 to releasably latch the assembly 67 in its position forwardly adjacent the assembly 66 over the open ends 37 of the coin chutes 29 while the springs 47 are returning the plate 39 rearwardly to drive the shaft 48, the cam arms 44, the handle 95, the ratchet discs 97, and the arms 48b to their starting positions.

In their normal positions the arms 67a are held against arms 48a by the action of springs 67d out of the paths of the respective pins 91. When, however, the handle 95 is operated to rotate the shaft 48, the arms 48a are moved away from engagement with the locking members 67a which are then yieldably urged against the then rearwardly moving pin 91. The springs 67d move the locking levers 67a to the position of locking engagement with the pins 91 when the assembly 67 reaches the position shown in Fig. 10, at which the pins have passed beyond the shoulders 67c. At the end of the return movement of the shaft 48 the arms 48a rotating with the shaft engage the locking levers 67a and remove them from locking engagement with the pins 91 whereupon the springs 92 return the assembly 67 to its forward position shown in Fig. 6.

The assembly 66 is automatically releasably locked in its rearward or depositing position (Fig. 10) while the assembly 67 is being returned to its forward position by the springs 92 as just described, to remove the coin retaining fingers 88 from the passages 74 so that any token or coin or a plurality of tokens or coins in the passages 74 will be deposited in the open ends 37 of the coin chutes. To assure that every token or coin so deposited in the coin chutes will reach their switch operating positions therein before the pins 63 are moved inwardly of the coin chutes, the plate 55 is releasably locked in the position at which the pins 63 are out of the coin chutes when the assembly 67 is moved forwardly to release coins from the passages 74.

Novel means for so locking the assembly 66 in a position for depositing coins in the coin chutes 29 comprises a pair of lugs 105 at opposite ends of the plate 55, and inverted L-shaped members 106 pivoted as at 107 at their lower ends on the frame members 11 and 12. Each member 106 has at its upper end a forwardly extending arm provided with a cam surface 108 and an upright arm provided between the pivot 107 and the forwardly extending arm with a latching member 109, providing at its lower end a laterally extending flange or projection 111 and at its upper end a forwardly extending shoulder 112.

The rearwardly extending lugs 79 on the arms 75 in the coin receiving position of the assembly 66 engage the cam surfaces 108 for yieldably holding the members 106 against the action of

springs 113 in a slightly rearwardly tilted position, as shown in Fig. 6. When the lugs 79, swinging rearwardly with the assembly 66, pass beyond the forwardly extending shoulders 112, the springs 113 swing the members 106 forwardly, as shown in Fig. 10, to move the shoulders 112 into engagement with edge portions 114 of the lugs 79 and to move the flanges 111 into engagement with the lugs 105. In that manner the assembly 66 is releasably locked in the depositing position shown in Fig. 10 and the plate 55 is positively held in such position that the switch operating means 63 are outside of the respective coin chutes 29. Thus when the springs 92 return the assembly 67 forwardly, the coin retaining fingers 88 are removed from the coin passages 74 in the releasably locked assembly 66 for releasing any coins therein. The released coin or coins will gravitate through the open lower ends of the passages 74 into the open upper ends 37 of the respective coin chutes 29.

The releasably locked assembly 67 is adapted to be released by the pins 91 engaging the cam surfaces 108 during the return forward movement of the assembly 66 to tilt the members 106 rearwardly sufficiently to cause the shoulders 112 to disengage the lugs 79 and the flanges 111 to disengage the lugs 105. The springs 62 thereupon swing the released plate 55 upwardly to move the pins 63 into the coin chutes 29, causing each coin so deposited in the curving portions 31 to actuate the corresponding pin 63 whereby to operate its contacts 58 as already described.

To prevent the springs 77 from returning the assembly 66 from its depositing position (Fig. 10) to its receiving position (Fig. 6) too rapidly when it is released, a dash pot 115 is pivoted on the forward frame extension 15, as shown at 116 in Figs. 1, 3, and 4. The dash pot 115 is provided with a reciprocable plunger 117 pivotally connected as at 118 to an arm of a bell crank lever 119 which is pivotally mounted on the pin 76 and which has another arm pivotally connected to one of the arms 75 by the pin 78.

The handle 95 and the various means operable thereby are releasably locked to prevent operation thereof unless a coin has been deposited in at least one of the passages 74, by novel means which will now be described. A pair of levers 121 are pivoted by screws or other suitable means 122 to the upright portions 13 and 14 of the frame members 11 and 12 respectively. Each lever 121 extends rearwardly from its pivot and is beveled at its rear end for cooperation with a roller 123 on each ratchet disc 96. Intermediate its ends each lever 121 has an upwardly extending lug or projection 124 to the upper end of which is secured one end of a spring 125. The other end of each spring 125 is secured to an arm 126 of a bell crank lever 127 pivoted by the screw 122 to the upright frame member 11, 12.

The bell crank levers 127 are yieldably held in the positions shown in Fig. 1 by springs 128 respectively secured at their opposite ends to the upright frame members 11 and 12 and the upper ends of bell crank lever arms 129. Those lever arms 129 are engageable with a closure plate 131 supported at its opposite ends below the level of the connecting member 22 by its end extensions 132 reciprocable in the slots 17 in the upper ends of the frame portions 13 and 14, and by screws 134 in the frame member 22 passing through elongated slots 135 in the closure plate 131. The closure plate 131 is movable

forwardly against the action of springs 136 under the frame member 22 to close the coin receiving apertures 27 by the arms 129 of the bell crank levers 127 and is movable in the opposite direction by the springs 136 to open those coin receiving apertures 27.

The arm 129 of each bell crank lever 127 is provided at its upper end with a pin or projection 137 co-acting with novel latching means for preventing the operation of the handle 95 unless a coin is in at least one of the chambers 74. Such means comprises latch members or arms 138 fixed on a rock shaft 139 journaled in the upright portions 13 and 14 of the frame members 11 and 12 forwardly of the forward position of the strap 82. Those latch members 138 are at the opposite ends of the shaft 139 outwardly of the frame members 11 and 12 and extend rearwardly for engagement with the pins 137. Each latch member 138 is provided at its rear end with a slot 141 in its upper side and rearwardly adjacent the slot 141 with an upstanding projection having an inclined or cam surface.

The cam surfaces 142 normally are in engagement with the pins 137 to hold the latch members 138 in the position shown in Fig. 1 against the action of springs 143. The slots 141 are adapted to receive the pins 137 therein when an attempt is made to operate the handle 95 without a coin being in any of the passages 74, thus locking the arms 129 of the bell crank levers against forward movement. In that locked position of the bell crank levers the rear ends of their arms 126 are in the paths of the shoulders 102 provided on the ratchet discs 96 by the enlarged slots 99 and will thus prevent rotation of those ratchet discs and hence of the handle 95.

To prevent moving the latching members 138 to their latching positions as just described when a coin of proper denomination is in at least one of the passages 74, the rock shaft 139 has fixed thereto a plurality of depending feeler members 144 having rearwardly extending lower end portions 145 and spaced along the shaft in respective alignment with a plurality of apertures 146 in the forward coin transferring bar 71 of the assembly 66. Each aperture 146 communicates with one of the passages 74, and the feeler members 144 are rockable with the shaft 139 to move the end portions 145 into and out of the respective chamber passages 74.

During the operation of the handle 95 to rotate the discs 96, the rollers 123 will engage the beveled rear ends of the levers 121 and will cam those levers upwardly about the pivots 122. That motion is transmitted to the bell crank levers 127 by the springs 125 to swing the bell crank lever arms 129 forwardly against the action of the springs 128 and to move the arms 126 out of the path of the shoulders 102 where they are engageable by the arcuate portions 101 of the ratchet discs 96 and ride on those arcuate portions until the discs and handle return to their starting position.

If a coin of proper thickness or, in other words, denomination, is in at least one of the passages 74, it is thus engageable by the corresponding feeler end portion 145 to prevent rotation of the rock shaft 139 sufficiently to move the latching members 138 into latching engagement with the pins 137. During such forward movement of the arms 129 they engage the closure plate 131 and move it to a position to close the apertures 27. If the coin or coins in the assembly 66 are of improper thickness, or in other words of im-

proper denomination, or if no coin is in any of the passages 74, the rock shaft 139 is free to be rotated by the latching members 138 actuated by the springs 143 when the pins 137 disengage the cam surfaces 142 until the pins 137 engage in the slots 141, thus locking the handle 95 against operation.

If a knife blade or other implement be inserted through the coin receiving apertures 27 into one of the passages 74 in an attempt to hold the feeler end portions 145 whereby to prevent rotation of the shaft 139 and the latching member 138, and thereby to obtain a free operation of the control apparatus, the closure plate 131 will engage that knife blade or implement and will be stopped in its forward movement to close the apertures 27. Such stopping of the closure plate 131 prevents the arms 129 of the bell crank levers 127 from swinging forwardly sufficiently to remove the arms 126 out of the paths of the shoulders 102, and thus prevents operation of the handle 95.

For detecting and ejecting spurious coins such as magnetic slugs which may be of a diameter and thickness to adapt them for insertion into the passages 74, and to prevent the locking action controlled by the feeler end portions 145, novel means is provided and includes a transverse bar 147 which is slidably secured on a plurality of screws or other elongated headed members 148 between the heads and the rearward transferring bar 72 of the assembly 66. The bar 147 is located rearwardly of and substantially parallel to the rearward bar 72 and is provided at its opposite ends with extensions 149 projecting through the elongated apertures 21 in the frame members 11 and 12 for connection with suitable springs 151 adapted yieldably to hold the bar 147 in such a position that the extensions 149 are in the forward ends of the apertures 21.

The bar 147 carries at its rear face a plurality of magnets 152 secured thereon by iron or other magnetic screws 153, extending forwardly beyond the bar 147 and respectively arranged in alignment with a plurality of flared apertures 154 in the rearward bar 72, and in communication with the passages 74. Thus during the first portion of the transferring movement of the assemblies 66 and 67, the screws 148 move through the bar 147, the springs 151 holding the bar 147 in its forward position. In other words, the assembly 66 is moved rearwardly, bringing the magnetic screws 153 through the apertures 154 into proximity with a coin in any of the passages 74. Thereafter the magnet-carrying bar 147 is moved with the assemblies 66 and 67 against the action of the springs 151.

The magnets, through the screws 153, serve to hold magnetic slugs which may have been inserted in any of the passages 74 after the retaining pins 88 have been removed therefrom to release genuine tokens or coins into the coin chutes 29. During the return movement of the assembly 66, the magnet-carrying bar 147 is moved with those bars by the springs 151 until the extensions 149 engage the forward ends of the respective apertures 21. The magnets, meanwhile, hold the magnetic slug or slugs in the passages 74. When, however, the extensions 149 engage the forward ends of the apertures 21, the magnets and the bar 147 are stopped, but the springs 77 governed by the dash pot 115 continue the forward movement of the assembly 66, thus moving the magnetic slug or slugs away from the screws 153, thereby causing any such slug or

slugs to be released. By reference to Fig. 6 it will be seen that such release of the magnetic slug or slugs occurs when the assembly 66 is just rearwardly of its forward position so that the released slug or slugs will gravitate from the passages 74 and will drop to the glazed in sheet 35, where they are visible and accessible from outside the apparatus.

Where the novel apparatus is employed to control the vending units of a vending machine or any similar device, the operating cycle of which requires an appreciable time, it is desirable to provide means for preventing subsequent operation of the control apparatus until the vending units controlled thereby have completed their operating cycle, and for thereafter automatically rendering the control apparatus of the invention operable. Such means comprises, as shown in Figs. 5, 6, and 10, a solenoid 155 secured as at 156 to the inner face of the upright frame member 12 and having a reciprocable plunger 158, and a link 159 connecting the solenoid plunger 158 with an end of one of a pair of detents or levers 161, one such detent 161 being fixed at each end of a shaft 162 journaled at its opposite ends in the frame members 11 and 12. The detents 161 are normally yieldably held against stop pins 163, as shown in Fig. 6, by springs 164, and are movable against the action of those springs when the solenoid 155 is energized into the path of the closure plate 131 to hold it in closed position.

Suitable switch means including a pair of electrical make-and-break contacts 165 is connected in series with one of a pair of solenoid conductors or leads 166 by conductors 167 for controlling the solenoid 155. Those contacts 165 are operable, as shown in Fig. 5, by means for closing the contacts each time the discs 96 are operated, and for opening those contacts after a predetermined time, or, in other words, after completion of the operating cycle of the device controlled by the novel control apparatus. Such means comprises any suitable timing means shown diagrammatically at 168 in Figs. 3 and 5, which is energizable from one of the discs 96 for a predetermined timing operation, a lever 169 operable by a pin 171 on one of the discs 96 for winding or otherwise energizing the timing means 168 during each coin transferring operation of the discs 96 and the handle 95, and means 172 driven by the timing means 168 for closing and opening the contacts 165.

As already suggested, the particular timing means forms no part of the present invention, and since many suitable timing means are well known in the art, it is not disclosed in detail. Briefly, the switch contacts 165 are normally held open, for example, against the resiliency of one of those contacts by the means 172. During each coin transferring operation of the ratchet discs 96, the pin 171 engages the lever 169 to wind or otherwise to energize the timing means 168 and to move the means 172 away from the engaged contact 165, the resiliency of which causes it to move into electrical contact with the other contact 165, closing the circuit for energizing the solenoid 155. The energized timing means 168 thereafter drives the means 172 in the opposite direction for the predetermined period of time at the end of which the means 172 engages the contact 165 and moves it to the open position for breaking the solenoid circuit. The springs 164 thereupon remove the detents 161 out of the path of the closure plate 131 and the springs 136

return the closure plate to its initial position, opening the coin receiving apertures 27.

In normal operation of the control apparatus, a patron drops one or more proper tokens or 5 coins in the coin passages 27 for controlling one or more selected operable devices, such as merchandise or amusement vending machines which are correlated each with one of said passages. The insertion of a coin in any such passage 10 places the respective feeler member 145 (see Fig. 6) which shifts the shaft 139 and effects the release of a handle locking mechanism, that is, members 138 and 129 to permit operation of the handle 95. As the handle is moved downwardly, 15 the shaft 48 is oscillated through a given arc and the cam arm 44 moves from the position shown in Fig. 6 to that shown in Fig. 10. This movement of the cam arm shifts the plate 39 to the right as shown in Fig. 10 and the lugs or fingers 42 thereby advance the previously deposited coins 20 in the respective coin chutes not advanced since the deposition of the last coin therein. During such movement of the lever 95, the coin transferring assemblies 66 and 67 are also swung counter-clockwise as viewed in the drawings by the described mechanism to effect the transfer of a coin or coins therein to a position over the respective open or upper ends 37 of the corresponding coin chutes. The swinging of the member 67 to the coin delivering position enables the spring 113 to swing the latch 106 from the slightly rearwardly inclined position of Fig. 6 to the position shown in Fig. 10, which enables the edge 114 of member 79 to engage the shoulder 112 and 25 latch the said member 66 in coin delivering position.

As the handle is released by the operator, it is moved toward normal or upright position by the action of the spring 47, which also retracts the plate 39 and the fingers 42 from the position shown in Fig. 10 to the position illustrated in Fig. 6. The assembly 66 will have been latched in the coin depositing position against return movement by means of the latch member 106, and the assembly 67 will also have been latched momentarily, that is, during the return stroke of the handle 95, in the coin delivering position by reason of the engagement of the latch 67a with the pin 91, which members are released by the member 48a as the handle approaches its normal or upright position.

The assembly 67 then starts its return movement to the normal position under the action of the spring 92, the tokens or coins in the respective coin passages 74 being thereupon released and dropped into the open ends 37 of the corresponding chutes and gravitate to the position or positions indicated by the left-hand or uppermost coin in Fig. 6. Prior to the dropping of the coin or coins as described, the pins 63 will have been retracted or moved downwardly from obstructing position in the coin chutes by reason of the swinging action imparted to the plate 55 by cam surfaces 46 of the cam arms 44 and the plate will be retained momentarily in the depressed position shown in Fig. 10 by reason of the engagement of the lug 105 with the flange 111 of the member 106, said member 106 having been moved to the position of Fig. 10 from that shown in Fig. 6 by the swinging action imparted to the member 106 by the action of the pin 91 on the cam surface 43. Such counter-clockwise movement of latch 106 releases the frame member 66, which is then returned, under the control of the dash pot 115, to the normal or upright position

by means of the spring 71. The rearward or counter-clockwise movement of member 106 not only releases the frame 66 as above mentioned, but also effects the movement of the flanges 111 out of the path of the lugs 105, whereupon the spring 113 swings the plate 55 counter-clockwise from the position shown in Fig. 10 to the position of Fig. 6, thus causing the pin or pins 63 to engage a newly deposited coin or coins in the passages 38 for moving the contact arms 54 into circuit closing relation. Concurrently with the movement of the handle 95 by the operator to initiate the foregoing operations, the timer 163 will have been energized by the swinging movement of the arm 169, imparted thereto by the stud 171 carried by the disc 96. Such movement of the arm 169 will have caused the member 172 to move to the left as viewed in Fig. 5 to enable the contact arms 165 to close the circuit of the solenoid 155, which during its period of energization retains the latch 161 in the position of Fig. 10 to retain the slideable plate 131 in coin-slot closing position, to which closing position said plate will have been moved, as the handle 95 was initially swung downwardly by the operator, by reason of the upward swinging movement imparted to the latch member 124 by the roller 123 of the disc 95 and the accompanying clockwise movement of the member 127, the arm 132 of which will have moved the plate 131 to the right, as viewed in Fig. 1.

As the timer 163 operates, the member 172 thereof will after a predetermined interval separate the contacts 165 and thereby open the circuit of the solenoid, at which time the operating cycle of the control device will have been completed. De-energization of the solenoid enables the spring 164 to move the latch members 161 to the inoperative position shown in Fig. 6, and permits the spring 136 to retract the plate 131 to open the coin passages 21, and enables the latch member 127 to return to the position of Fig. 1, to prevent the operation of handle 95 without first inserting another coin.

While I have illustrated and described a preferred embodiment of my invention, many modifications may be made without departing from the spirit of the invention, and I do not wish to be limited to the precise details of construction set forth, but desire to avail myself of all changes within the scope of the appended claims.

Having thus described my invention, what I claim as new and desire to secure by Letters Patent of the United States is:

1. In a control apparatus of the coin controlled class, a plurality of coin chutes having inlet openings, a member having a plurality of coin receiving passages offset from and corresponding in number to the number of chutes, means for moving said member to and from a depositing position relative to said inlet openings, coin retaining means in each said passage for retaining a coin therein until said member is in its depositing position, means for operating said retaining means to release the coin in said position, and fraud preventive means including means for releasing an improper coin from a passage at a position removed from the depositing position relative to the coin chute.

2. In control apparatus of the coin controlled type, a chute having a coin receiving opening, pivotally mounted coin receiving and carrier means normally offset from said chute opening, said carrier means comprising a pair of coin engageable separable assemblies, means for swing-

ing said assemblies in unison to coin depositing position with respect to said chute opening, and means for separating said assemblies to release a coin therein for deposition in said chute.

3. In control apparatus of the coin controlled type, a chute having a coin receiving opening, a pivotally mounted coin receiver and carrier member normally offset from said chute opening, said member comprising a pair of separable assemblies provided with coin engageable means, means for swinging said assemblies in unison to coin depositing relation with respect to said chute opening, means for releasably locking one of said assemblies in said depositing position, means for moving said other assembly away from said locked assembly to release a coin therein for deposition in said chute opening and return said unlocked assembly to original position, and means for releasing said locked assembly for return of the same to original position.

4. In control apparatus of the coin controlled type, a chute having a coin receiving opening, a pivotally mounted coin receiver and carrier member normally offset from said chute opening, said member comprising a pair of separable assemblies provided with coin engageable means, means for swinging said assemblies in unison to coin depositing relation with respect to said chute opening, means for releasably locking one of said assemblies in said depositing position, means for moving said other assembly away from said locked assembly to release a coin therein for deposition in said chute opening and return said unlocked assembly to original position, and means operable by said unlocked assembly during the return movement thereof for releasing said locked assembly for return of the same to original position.

5. In control apparatus of the coin controlled type, a swingable coin receiver, a coin chute, means for swinging the receiver with a coin therein to a position of said chute and arranged for depositing the coin in said chute, means for arresting the coin in a given position within said chute, a movable switch comprising a member adapted to be projected into said chute within said given coin position, said switch being arranged for operation by said member upon engagement of the latter with a coin in said chute, and means for moving said switch and member for projecting said member into said chute into engagement with a coin deposited in said given position for operating the switch.

6. In a control apparatus of the coin controlled type, a coin chute adapted to receive coins one at a time, means for moving a deposited coin from a given position in said chute, means for arresting a subsequently deposited coin in said given position in said chute, a swingable coin receiver adapted to receive a coin, means for swinging said receiver to a position above said chute, means for releasing the coin in said receiver for deposition in said given position in the chute, movable control means comprising circuit closing means and a member for operating said circuit closing means, and means for moving said control means in a direction to project said member into contact with a coin in said given position in said chute for operating the circuit closing means.

7. In a coin controlled apparatus, a plurality of coin chutes each provided with means for arresting a coin in a given position therein, a movable member provided with switches each associated with one of said chutes and each provided with a switch operating member adapted to be

moved into engagement with a coin in the given position of the respective chute for closing the corresponding switch, a movable coin receiver provided with coin passages corresponding in number to the number of said chutes, mechanism for operating said coin receiver for effecting the transfer of a coin or coins therein to the given position or positions in the corresponding chute or chutes, and means for operating said movable member for moving said switch closure members into engagement with the coin or coins in the said given position in corresponding chutes.

8. A coin controlled apparatus comprising a plurality of coin chutes each provided with means for arresting a coin in a given position therein, each of said chutes being provided with an aperture for the admission of a switch operating member into the chute for engagement with a coin in said position therein, coin-receiving and transferring means provided with coin passages corresponding in number to the number of said chutes, means for locking said coin receiving and transferring means in a given position, means operable by an inserted coin for releasing said locking means, operating means for said coin receiving and transferring means for operating the same when unlocked for effecting the transfer of one or more coins therein to the said position or positions in the corresponding chutes, a movable member provided with switches each associated with one of said chutes, each of said switches having a switch operating member adapted to be

5 moved by said movable member through the aperture of the corresponding chute for engagement with a coin in the said given position therein to effect the closure of the respective switch, and mechanism controlled by said operating means for actuating said movable member following the deposit of a coin or coins in said chute or chutes.

9. In a control apparatus of the coin controlled type, a plurality of coin chutes each provided with means for arresting a coin in a given position therein, a plurality of switches each operatively associated with one of said chutes, an actuating member for each switch adapted to be moved into engagement with a coin in the respective given position in the corresponding chute to operate the respective switch, mechanism having coin recesses for receiving coins and being operable for transferring each of the same into said given position of the associated chute, locking means for said mechanism provided with a member in each recess and each being operable by a coin in the corresponding recess for unlocking said locking means, means for operating said coin receiving and transferring mechanism when released by an inserted coin, and means operable by said operating means for effecting the movement of said switch actuating members for causing engagement of the same with coins transferred into the respective given positions in said 20 chutes for effecting the closure of the corresponding switches.
